UNITED STATES PATENT OFFICE.

CHARLES E. LYNCH, OF BROOKLYN, NEW YORK.

SHOE CONSTRUCTION

1,239,411.

Specification of Letters Patent. Patented Sept. 4, 1917.

Application filed November 27, 1916. Serial No. 133,706.

To all whom it may concern:

Be it known that I, CHARLES E. LYNCH, a citizen of the United States, residing at Brooklyn, in the county of Kings and State of New York, have invented certain new and useful Improvements in Shoe Constructions, and do hereby declare the following to be a full, clear, and exact description of the invention, such as will enable others skilled in the art to which it appertains to make and use the same.

This invention relates to shoe construction, and more particularly to that type of shoe in which reinforcement is provided for fallen arches.

It has for an object to provide an improved form of shoe construction in which a reinforcing webbing is included in the normal shoe construction to bind and support a portion of the foot of the wearer having fallen arches.

A further object of this invention is a provision of a raised portion of the insole of the shoe to arch a foot in the instep thereof.

A further object of this invention is the provision of a shoe having a raised insole therein having one portion thereof supported by padding, a reinforcing webbing with 30 in the upper of the said shoe attached to the sole with the upper and said reinforcing webbing being secured within the upper and having its end carried by the normal fastening means for the shoe.

35 A further object of this invention is a provision of a shoe having the normal outward appearance of an ordinary shoe, but having the insole therein raised over the shank of the sole, said shoe also having an 40 enlargement thereof rearward of the raised portion of the insole, and having a reinforcing webbing attached to the welt in the manufacture of the shoe having said reinforcing webbing raised within the shoe to 45 where the normal fastening means is provided, which also includes the end of the reinforcing webbing.

Further objects will be apparent from the following specification, appended claims and drawings, in which—

Figure 1 is a perspective view of a shoe showing the features of this invention applied thereto and showing parts broken away for sake of clearness,

Fig. 2 is a cross sectional view centrally thereacross, and

Fig. 3 is a fragmentary perspective view showing the inside of the shoe.

In the manufacture of shoes to meet special requirements, it is desired to provide a shoe having the general exterior appearances of the ordinary shoe but to incorporate characteristics therein which adapt said shoe to the foot of a wearer requiring special consideration, and as shown by the following description, provision is made for supporting the arch of a foot as by a reinforced insole, also permitting the desired binding of the foot about the instep as by an included reinforcing webbing through which the ordinary fastening means of the shoe passes and the further provision of a slightly bulged or enlarged portion of the shoe rearwardly of the raised portion of the insole.

Referring to the drawings in which the several features of this invention are clearly disclosed, 10 indicates the upper of a shoe having the sole 11 attached thereto, the heel 12 and the slightly reduced shank 13. Within the shoe is the usual insole 14 which over the shank and adjacent to one side of the shoe is raised as at 15 as by a filler 16, which is placed between the insole and shank 13. The upper and sole are bound as by the usual welt 17 and where the upper is attached to the shank 13 to one side of the shoe, a reinforcing webbing 18 is also included as at 19 together with the usual lining 20 which may be of a thin material. The reinforcing webbing 18 rises within the shoe and has its end underlie the edge of the shoe in which the eyelets or other fastening means 21 are placed so that as the shoe lace passes through said eyelets it may exert the desired tension on the reinforcing webbing 18 to thereby raise the arch of the foot to the desired degree. This reinforcing webbing is also attached to the inner face of the upper, as by the light rows of stitching 22 which pass through the webbing near its edge.

As shown in Fig. 3, the insole 14 is raised as at 15 on the inner side of the foot over the shank 13 and in cases requiring this type of shoe it frequently occurs that the heel of the shoe need be enlarged somewhat so the upper is bulged as at 23 and the in-

sole may also have a slight offset 24 formed thereon as this bulge permits the foot fitting more snugly in the shoe and gives the general lines of the shoe the appearance of one of normal shape.

It is apparent that modifications may be made in view of the foregoing and that no limitation is implied by the limited number of views shown therein, but the combined 10 use of a partially raised insole which may be held in raised position by a reinforcing webbing having one edge thereof attached to the shank and having its opposite edge carried by the fastening means of the shoe 15 to permit the desired binding action being had together with the enlarged heel portion of the shoe present the novel combination and more explicitly outline the scope of the appended claims.

20 Having thus described this invention, I claim:

1. A shoe of the class described, comprising a sole, an insole having one marginal edge higher than the other marginal edge, 25 an upper and a lining secured to said sole, said higher marginal edge of the insole leaning against said lining and a reinforcing webbing secured to said sole.

2. A shoe of the class described, comprising 30 a sole, an insole raised over the inner portions of the shank thereof, padding between the shank of the sole and the raised insole, an upper and a lining secured to said sole, said insole being relatively wider than 35 the shank portion of the sole and having one edge thereof leaning against said lining, and a reinforcing webbing secured to said sole between the upper and lining under the raised insole to brace the upper edge of the 40 raised insole.

3. A shoe of the class described, comprising a sole, an insole raised over the inner portions of the shank of said sole, padding between said shank and said raised portion, 45 an upper and a lining secured by said stitching to the sole, said insole being relatively wider than the shank portion of the sole and having one edge thereof leaning against said lining, and fasteners for the shoe passing through the lining, reinforcing webbing and upper.

4. A shoe of the class described, comprising a sole, an insole, an upper and a lining

secured to said sole, one edge of the insole overlapping with respect to the adjacent edge of the lining, and a reinforcing webbing secured to said sole.

5. A shoe of the class described, comprising an insole raised to underlie the inner portions of the astragalus and metatarsal 60 bones of a foot of a wearer, an upper and lining for said shoe, said insole being relatively wider than the shank of the sole and having one edge thereof leaning against said lining, and a reinforcing webbing secured at its edges between said upper and lining to bind the foot of a wearer and to brace said raised insole at and near its extreme edge.

6. A shoe of the class described, comprising 70 a sole, an insole raised over the inner portions of the shank thereof, padding between the shank of the sole and the raised insole, and a composite unitary structure involving an upper, a lining and an interposed reinforcing webbing secured to said sole beneath the raised insole, said insole being relatively wider than the shank of the sole and having one edge thereof leaning against said lining.

7. A shoe of the class described, comprising 75 a sole, an insole raised over the inner portions of the shank thereof, padding between the shank of the sole and the raised insole, and a composite unitary structure involving an upper, a lining and an interposed reinforcing webbing secured to said sole beneath the raised insole, so that the lower margin of said structure serves as a supporting wall for said raised insole and 80 padding, said insole being relatively wider than the shank of the sole and having one edge thereof leaning against said lining.

8. A shoe of the class described, comprising 85 a sole, a raised insole over the inner portions of the shank thereof, padding between the shank of the sole and the raised insole, a composite unitary structure involving an upper, a lining and an interposed reinforcing webbing secured to said sole beneath the raised insole, and a fastening device extending clear through the upper edge 90 of said structure.

In testimony whereof I affix my signature.

CHARLES E. LYNCH.
